UNITED STATES PATENT OFFICE.

NATHAN WEIDNER, OF BROOKLYN, NEW YORK.

DESIGN FOR A BEVERAGE CONTAINER.

Application filed March 11, 1927. Serial No. 21,099. Term of patent 3½ years.

To all whom it may concern:

Be it known that I, NATHAN WEIDNER, citizen of the United States, and resident of Brooklyn, in the county of Kings and State of New York, have invented a certain new, original, and ornamental Design for Beverage Container, of which the following is a specification, reference being had to the accompanying drawing, forming part thereof.

I claim:

The ornamental design for a beverage container, as shown.

Signed at New York, in the county of New York and State of New York, this 8th day of March, A. D. 1927.

NATHAN WEIDNER.
